UNITED STATES PATENT OFFICE.

EDMUND A. HOENNER, OF AKRON, OHIO, ASSIGNEE TO THE FINESTONE TIRE AND RUBBER COMPANY, OF AKRON, OHIO, A CORPORATION OF OHIO.

ROTARY CUTTER.

Application filed July 29, 1924. Serial No. 723,858.

This invention relates to rotary bias cutters such as are used in the preparation of tire building materials, and has for its object the provision of means in combination with the cutter roll for effectively removing the cut strips.

An understanding of the invention will be the more readily attained by consideration of the following brief description thereof in connection with the accompanying drawings, it being understood that the invention is not limited to the specific apparatus shown or described.

Of the drawings:

13 Figure 1 is an elevation of a cutter roll illustrating the manner of mounting a strip-removing means for cooperation therewith;

Figure 2 is a diagrammatic view in which a strip-removing attachment is shown in 20 such position as to apply the cut strips to a conveyor; and

Figure 3 is a detail elevation, partly in section, of the attachment.

Referring to the drawings, 10 is a bias cutter roll having helically arranged knives 11, 11 thereon. Cooperating with the knives 11 on the roll 10 is a pressure or abutment roll 12, the roll 12 being adapted to cut or pinch apart fabric lying on the knives 11. 30 The fabric, indicated at 13, is preferably so supplied to the roll 10 that it will lie in circumferential condition on the roll when passed between it and the pressure roll 12. To this end the fabric 13 may be led over rolls 14 and 14^a.

For carrying cut strips of fabric, indicated at 13^b, 13^a, a conveyor 15 is employed, the conveyor being trained over main pulleys 16 and 17 and preferably being arranged to 40 travel in a circumferential path against the roller 10 by being trained over a pulley 18 situated closely adjacent the nip of rolls 12 and 10 on the fabric issuing side thereof.

It has been found that without the use of 45 an attachment for removing the strips 13^b from the cutter roll, they tend to travel around with the same and to be ruined by becoming entangled with the stock to be cut, etc. This was found to be especially true in 50 the cutting of comparatively wide strips of fabric. Accordingly, after considerable experimenting, it was found that an air blast so directed as to remove the leading ends of the cut strips was a solution of the difficulty. 55 A suitable device is shown in the drawings at

10 and comprises a tubular nozzle 19^a having a series of apertures 19^b therein, air being supplied to the nozzle by suitable piping 19^c.

It is to be noted that the nozzle 19 is so directed as to direct the air at substantially 60 the angle of the knives on the roll 10. This effects a lifting of the leading end of the fabric strips 13^b and an application thereof to the belt 15, as will be apparent from a consideration of Figure 1, the front face of roll 65 10 being rotating as indicated by the arrow. The air tends to travel between the knives a substantial distance and, accordingly, lifts a large area of the leading end of the fabric from between the knives 11 and applies it to 70 the belt 15, whereby the remainder of the strip will be drawn from between the knives by the travel of belt 15 alone.

Modifications of the invention may be resorted to without departing from the spirit 75 thereof or the scope of the appended claims.

What I claim is:

1. A rotary cutter comprising a roller having a series of helically arranged knives thereon, a pressure roller adapted to press 80 sheet material against said knives, means for feeding the material between the rollers, a conveyor for receiving the cut strips of material, and an air blast nozzle arranged adjacent one end of the cutter roller and 85 so positioned as to direct a blast of air under the leading ends of the cut strips of material at substantially the same angle as the knives and apply the same to said conveyor.

2. A rotary cutter comprising a roller 90 having a series of helically arranged knives thereon, means for feeding sheet material onto the knives, means cooperating with the knives for cutting the material, a conveyor for carrying the cut strips from the cutter, 95 and means adapted to direct a blast of air under the leading ends of the strips on the cutter roller at substantially the same angle as the knives to apply the strips to the conveyor.

3. A rotary cutter comprising a roller having a series of helically arranged knives thereon, means for feeding sheet material to the knives, means cooperating with the knives for cutting the material, and means 105 for directing an air blast under the leading ends of the cut strips to remove the same from between the knives, said means being positioned to direct the blast substantially 110 at the same angle as the knives.

4. A rotary cutter comprising a roller having a series of helically arranged knives thereon means for feeding sheet material to the knives, means cooperating with the knives for cutting the material, conveyor means for receiving the cut stock from the cutter, and means for forcing the leading ends of the cut strips of material from between the knives. 15
5. A rotary cutter comprising a roller having a series of knives helically arranged

thereon, means for feeding stock sheet material onto the roller, means cooperating with the knives for cutting the material, conveyor means for receiving the cut stock from the cutter, and means for forcing the leading ends of the cut strips of material from between the knives onto the conveyor means to remove them from the roller.

EDMUND A. HOENER.
